UNITED STATES PATENT OFFICE.

JOHN H. HESS, OF CALEDONIA, MISSOURI.

SHOE-LACE HOLDER.

1,064,143.

Specification of Letters Patent. Patented June 10, 1913.

Application filed March 8, 1912. Serial No. 682,480.

To all whom it may concern:

Be it known that I, JOHN H. HESS, a citizen of the United States, residing at Caledonia, in the county of Washington, State of Missouri, have invented certain new and useful Improvements in Shoe-Lace Holders; and I do hereby declare the following to be a full, clear, and exact description of the invention, such as will enable others skilled in the art to which it appertains to make and use the same.

The present invention is directed to improvements in shoe-lace holders, and has for its object to produce a device for conveniently securing the knotted portion of a shoe-lace to prevent the same from becoming accidentally untied.

With this and other objects in view, the invention consists in certain novel features of construction, combination and arrangement of parts as will be hereinafter fully described and claimed.

In the drawing: Figure 1 is a front elevation of a shoe showing the device in use thereon. Fig. 2 is a side elevation of the same removed from the shoe. Fig. 3 is a plan view of the device, the plates being spread apart. Fig. 4 is a sectional view on line 4—4 of Fig. 1.

The device consists of a pair of sheet metal plates 1 and 2, the upper edges of which are provided with spaced eyes 3, which when in registered relation are adapted to receive the pin 4, thus hingedly connecting the plates.

The plate 2 is formed with a rectangular opening 5, the side bars 6 formed thereby being provided with a series of alined spurs 7, the same being adapted to bite into the unknotted ends of the shoe-lace, when the knot formed by the tying of the same is positioned in the opening 5. A rod 8 is slidably mounted in a pair of guides 9 carried by the plate 2, the inner end of said rod being provided with a head 10, while the outer end of the rod 8 projects a sufficient distance beyond one of the side edges of the plate 2 so that the same may be conveniently grasped for sliding said rod, the head of

which being adapted to engage or disengage with the catch 11 carried by the plate 1. The catch 11 is formed from a strip of sheet metal and is angular in cross section. The horizontal web 12 is soldered to the plate 1 and is of sufficient width to position the vertical web 13 in spaced relation with the plate 1 to accommodate the head 10 carried by the rod 8.

In use the plate 1 is placed under the knotted end of the shoe-lace and the plate 2 is then swung upwardly, whereupon the spurs carried thereby will engage the part of the unknotted portion of the lace, while the knot projects through the opening 5. The rod 8 is then forced inwardly until the head thereof engages the latch 11, thus firmly locking the plates together, and preventing the accidental untiring of the lace. When it is desired to untie the lace it is only necessary that the rod 8 be operated to withdraw the head thereof from engagement with the catch, whereupon the plate 2 may be swung downwardly and the device removed and the lace untied.

What is claimed is:

A shoe-lace holder consisting of a pair of plates having their upper edges hingedly connected, one of said plates being provided with side bars to produce a rectangular opening, spurs carried by the side bars, a catch carried by the other plate, and consisting of a vertical web spaced from the plate, alined guides formed upon the first named plate, a rod slidably mounted in the guides, a head formed upon the inner end of the rod, said head being adapted to engage the space between the web and plate when the same is swung against its coacting plate and the knot of a shoe-lace is positioned in the rectangular opening of the first named plate and is engaged by said spurs.

In testimony whereof, I affix my signature, in presence of two witnesses.

JOHN H. HESS.
